UNITED STATES PATENT OFFICE.

LOUIS S. LARSON, OF RACINE, WISCONSIN.

DESIGN FOR A WHIFFLETREE-HOOK.

SPECIFICATION forming part of Design No. 32,405, dated March 27, 1900.

Application filed February 21, 1900. Serial No. 6,116. Term of patent 7 years.

To all whom it may concern:

Be it known that I, LOUIS S. LARSON, a citizen of the United States, residing at Racine, in the county of Racine and State of Wisconsin, have invented and produced a new and original Design for a Whiffletree-Hook, of which the following is a specification.

This invention relates to a new and original design for a whiffletree-hook, and has for its object to provide a design of this character which shall be both useful and ornamental.

The feature of the present design resides in the substantially straight shank having a loop-shaped extremity which is elongated longitudinally of the shank and has its opposite longitudinal sides converged toward the shank and meeting at their conjunction therewith, the opposite end of the shank being rebent into a hook shape, which is disposed in a plane at substantially right angles to that of the loop, the outer side of the hook being bowed inwardly, as indicated at 6, at a point substantially midway of the opposite ends of the hook. The extremity 7 of the hook is pointed and bowed outwardly and also terminates at a point substantially opposite the intersection of the shank and the loop-shaped end thereof.

In the drawings, Figure 1 is a perspective view of a whiffletree-hook embodying the present design. Fig. 2 is a side elevation thereof.

Corresponding parts in both figures of the

drawings are designated by like characters of reference.

Referring to the accompanying drawings, 1 designates the substantially straight shank, which has one end formed into a loop shape 2, which is elongated longitudinally of the shank and has its opposite longitudinal sides 3 and 4 converged toward the shank and meeting at their intersection therewith. The opposite end of the shank is bent into a hook 5, which is disposed in a plane at substantially right angles to that of the loop, the outer side of the hook being bowed inwardly, as indicated at 6, at a point substantially midway of the opposite ends of the hook. The extremity 7 of the hook is pointed and bowed outwardly and also terminates at a point substantially opposite the intersection of the shank and the loop-shaped end thereof.

At the point of intersection between the shank and the loop-shaped end thereof is a hook-shaped projection 8, which is located upon the same side of the shank as is the hook 5 and in the same plane with the latter. This hook-shaped projection is bowed downwardly and has its pointed end terminating adjacent to the inner side of the hook 5 and inwardly from the extremity thereof.

What I claim is—

The design for a whiffletree-hook, as herein shown and described.

In testimony that I claim the foregoing as my own I have hereto affixed my signature in the presence of two witnesses.

LOUIS S. LARSON.
